UNITED STATES PATENT OFFICE.

HARRY A. CUMFER, OF CHICAGO, ILLINOIS, ASSIGNOR OF ONE-HALF TO THE FLINT-KOTE COMPANY, OF BOSTON, MASSACHUSETTS, A CORPORATION OF MASSACHUSETTS.

SHINGLE STRIP.

Application filed October 2, 1924. Serial No. 741,118.

This invention relates to improvements in shingle strips, and specifically contemplates so severing and slitting a continuous sheet of previously prepared roofing material as 5 to produce individual shingle strips, which when laid on a roof, present corresponding hexagonal areas of light, dark and shadow. The invention is characterized by the fact that the strips can be produced without any 10 waste in cutting and are self-spacing relative each other, when placed on a roof.

Briefly, the sheet of previously prepared roofing material may be completely severed centrally of its length and adjacent this 15 central line of severance at right angles thereto is also completely severed at predetermined intervals corresponding to the width desired. Communicating with each of the latter vertical lines of severance, is a 20 right angled cut, parallel to the central line of severance. From the latter line of severance are communicating diagonal lines of severance, the outer set of diagonal lines connecting with a relatively short line of 25 severance, again parallel to the central severing line. This relatively short line of severance communicates with right angled lines of severance, terminating at the edges of the roofing sheet. Further, a set of 30 opposed half hexagonal incisions are produced intermediate each complete line of severance. The individual strip thus produced has upper and lower straight edges while the sides are staggered relative to the upper 35 and lower edges, but parallel to each other, having semihexagonal incisions in the body thereof. The lower portion is then folded along the unbroken connecting lines upon the upper body portion, resulting in the 40 formation of a strip exhibiting perfect hexagonals, which when laid on a roof, presents a series of staggered or parallel hexagonals of alternately contrasting light and dark colors.

Many advantages will be apparent to those skilled in the art, among which may be mentioned the economy of construction, the self-spacing when laid on a roof, the reinforcing structural characteristics produced, and the attractive hexagonal areas of contrasting color presented to the eye.

In the drawings:

Fig. 1 is a plan view of a continuous roof-

ing sheet severed and incised to produce my improved shingle strip.

Fig. 2 is a plan view of the individual strip with the lower portion folded over the upper portion.

Fig. 3 is an edge view of the construction shown in Fig. 2.

Fig. 4 is a plan view of the strips assembled in place on a roof, illustrating one form of arrangement.

Referring in detail to the drawings, 1 designates as a whole a continuous sheet of 65 felt previously saturated with a waterproofing composition, and one or both surfaces of which may have imposed thereon a granular surfacing of a predetermined color, although in the preferred form of invention, one surface only may be coated with the granular material, the opposite surface presenting a plain appearance, for instance, black, where asphalt is used as the saturant. The granular material may be any color such as red, 70 green, gray, slate, etc.

As this sheet is fed forward, it is longitudinally severed centrally of its width along the line 2, and also vertically severed along the line 3 bisecting the line 2. The 80 lines 3 terminate in right angle severing lines 4, from which extend diagonals 5 and 6. The diagonal 5 terminates within the body of the material, while the diagonal line 6 has a short angular extension 7 parallel 85 to the central line of severance 2. The latter extension 7 terminates in a right angled severing line 8, which terminates adjacent the edges of the sheet to produce complete severance. Intermediate the edges of 90 each shingle strip are produced semi-hexagonal incisions 9 for a purpose hereinafter explained.

The individual shingle strip produced by severing a sheet of roofing material as described heretofore, has upper and lower straight parallel edges while the sides are staggered relative to the upper and lower edges, but the staggered lines per se are parallel to each other. The bottom portion of 100 the individual shingle strip along the unsevered lines between the extremities of the semi-hexagonal lines of severance, and the sides being staggered relative to the upper and lower edges, a novel and attractive appearance is the result. The extremities of

the incisions 9 within the body of the sheet preferably terminate at a point beyond the longitudinal central cross section, in order that the upper edge of the portion which is folded over may project beyond the upper edge of the portion which has not been folded. In this way, there is formed parallel or staggered hexagonal areas when the strip is laid on a roof in combination with other strips, while at the same time utilizing the particular construction of the strips to accomplish their own self-spacing.

One surface only may have granular material applied thereto of a predetermined color, while the other surface may be devoid of granular material and present the color of the waterproofing material, for instance, black, where asphalt is the waterproof material used. Thus, the assembled shingles on a roof present contrasting hexagonal fields of dark, light and shadow, as shown. Or, both surfaces may have granular material imposed thereon, of different colors, for instance, red and green, slate and red, etc.

Further, the shingles may be so laid as to present parallel areas of light and dark, or they may be staggered relative to each other.

The strips may be held in place by any suitable means, such as hollow nails, etc., driven into the body portion and concealed from view by the folded portion. The entire construction is extremely sturdy, and the reinforcing qualities of the doubled ply will be instantly appreciated. Furthermore, the finished roof gives the impression of solidity and strength, combined with beauty and attractiveness.

It is understood of course, that shingle strips can be produced from a sheet half as wide as that described, thus eliminating the line 2.

I claim as my invention:

1. A shingle strip of greater width than length, having two parallel straight sides and two sides staggered relative the straight sides but parallel with each other, having a semi-hexagonal incision in the body of the strip, and folded along the lines of the semi-hexagonal incision to produce hexagonal areas.

2. A shingle strip of greater width than

length having on one surface granular material of a predetermined color and the opposite surface presenting a contrasting color, having two parallel straight sides and two sides staggered relative the straight sides but parallel with each other, having semi-hexagonal incisions in the body of the strip, and folded along the lines of the semi-hexagonal incisions to produce hexagonal areas of contrasting color.

3. As a new article of manufacture, a roofing strip comprising parallel longitudinal edges, sides disposed partially at right angles and partially staggered relative the longitudinal edges, said sides being parallel with each other, the base of said strip exhibiting alternate cut-out portions and interposed tabs therebetween, and an integrally connected overlying portion folded upon the body portion, said overlying portion being of substantially the same configuration as the body portion.

4. As a new article of manufacture, a flexible roofing strip originally having on one surface granular material of a predetermined color and originally on the opposite surface a contrasting color, comprising a strip having parallel longitudinal edges, sides disposed partially at right angles and partially staggered relative said longitudinal edges but parallel with each other, the base of said strip exhibiting alternate cut-out portions and interposed tabs between the cut-outs, both being substantially semi-hexagonal in shape and an integrally connected overlying portion folded upon the body portion to produce hexagonal areas, the latter being of substantially the same configuration as the body portion, but of a contrasting color.

5. As a new article of manufacture, a flexible roofing strip comprising a body portion having granular material of a predetermined color imposed thereon, and an integrally connected overlying portion of the same configuration as the body portion, having a surface of contrasting color and disposed in a plane offset from the plane of the body portion.

HARRY A. CUMFER.
